UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

PRINTING DEVICE.

No. 853,588.

Specification of Letters Patent.

Patented May 14, 1907.

Application filed July 5, 1904. Serial No. 215,869.

To all whom it may concern:

Be it known that I, JOSEPH S. DUNCAN, a citizen of the United States, residing at Chicago, in the county of Cook and State of Illinois, have invented new and useful Improvements in Printing Devices, of which the following is a specification.

The object of this invention is to provide a printing device with a removable index card which can be readily changed to correspond alphabetically or otherwise with the subject-matter on the printing device.

To illustrate the invention and the manner of its use I have chosen a printing device of the type covered by Letters Patent No. 692994 dated Feb. 11, 1902 and referring thereto:—

Figure 1, is a plan view. Fig. 2, is an enlarged sectional view on the line 2—2 of Fig. 1. Fig. 3 is a detail view showing a modification of the preferred construction. Fig. 4, is an enlarged sectional view on the line 4—4 of Fig. 3.

In the drawings the printing device comprises a printing plate 5 which is held in a holder 6 in any suitable manner. The holder is constructed to carry a card in the space above the printing plate, the card bearing an impression of the type on the plate, as described in the patent aforesaid, but for simplicity I have indicated this card by the dotted line 7. The present invention is not in anywise limited to embodiment with a printing device of the character described but is intended and designed for embodiment with printing devices of various constructions, and its capabilities of such embodiment will be readily understood by those skilled in the art. In referring to a printing device herein it will be understood, therefore, that I mean and comprehend any printing device capable of use in a card index system.

The upper edge of the device is turned over or crimped in the form of a bead 8 for the whole or a portion of its length and an index card support 9 is cut out of the device and bent upward above the beaded edge 8. This sup-

port may vary in size according to the size of the index card 10 which it is desired to use. The upper edge of the support is preferably turned down to form a channel flange 11 and the side edges are turned up to form flanges or end stops 12. The index card is held in place on the support by the flanges 11 and 12 with its lower edge resting in the channel 13 formed between the bead 8 and the support.

To facilitate the insertion and removal of the index card, I prefer to bevel or cut away one or both of the upper corners of the support as shown in Fig. 1, so that the card can be readily inserted in the channels formed at the top and bottom of the support and pushed along to its proper position.

Instead of forming the flange 11 on the support in the manner heretofore described, I may form a flange 15 (Figs. 3, 4) at the top of the support at right angles thereto and make the side flange 16 to form channels substantially like the channel flange 11 as shown in Figs. 1 and 2.

The index card holder may be located at any position on the edge of the printing device. Index characters or other information can be printed or otherwise applied to the index cards to adapt the printing device for use in accordance with a card index system or for other purposes.

Without limiting myself to the exact construction and arrangement of parts herein shown and described, what I claim and desire to secure by Letters Patent is:—

A device of the character described comprising a holder, means on the holder for removably securing a printing device and a card thereon, one above the other, an index card support stamped from the holder and extending above its upper edge, said edge of the device being beaded to form a channel between itself and said support, and flanges at the top and ends of said support to hold a card in place thereon and in said channel.

JOSEPH S. DUNCAN.
